CLEAT

Richard H. Hagerty, Biscoe, Va.

Application October 19, 1937, Serial No. 169,855

1 Claim. (Cl. 36—59)

My invention relates to cleats and more particularly to that class adapted to be secured to the soles of sport shoes and the like.

One of the principal objects of my invention is to provide a cleat equipped with means for gripping the ground in a manner to maximize the gripping action and the comfort of the wearer and at the same time minimize the wear on the ground or other surface acted on; and furthermore, particularly in a type of cleat adaptable for attachment to the soles of baseball shoes, to minimize the liability of injury to the wearer and opposing players.

Another object of my invention is to provide a device of the above described character which is simple in construction, economical in manufacture and durable in use.

Other objects and advantages will be apparent from the following description, appended 20 claim and annexed drawing.

Referring to the drawing wherein like reference numerals designate like parts throughout the several views:

Fig. 1 is a bottom view of a sport shoe illustrating my invention attached thereto.

Fig. 2 is a side elevation of the toe plate.

Fig. 3 is a sectional view taken on a line 3—3 of Figure 1.

Fig. 4 is a plan view of a blank from which the 30 toe cleat is formed.

Fig. 5 is a plan view of a blank from which a modified form of cleat is fashioned.

For the purpose of teaching my invention I provide a sport shoe, preferably of the type worn 35 in playing golf, with the usual sole 5 of typical construction. Attached to the bottom of the sole 5 are a pair of my novel cleats comprising toe and heel cleats 6 and 7 respectively.

The toe cleat 6, in the preferred embodiment 40 illustrated in Figures 1 to 4 inclusive of the drawing, comprises a plate 8 of a substantially trapezium-shaped configuration in plan view having side, front and rear members 9, 10 and 11 respectively formed on the outer sides of said plate. 45 Each of said members are rounded on the ground engaging edges for permitting the same to easily penetrate the ground but preventing the same from unduly marring or roughing the surface thereof. Each of the members are offset and extend at right angles to the horizontal plane of the plate proper. The plate proper is preferably constructed of aluminum, and formed with a central aperture to minimize the weight of the device and each of the inner and outer faces of the 50 plate are rounded to prevent roughing of the

ground and the adhering of foreign matter to said faces. Suitable fastening means, for instance rivets 12, are secured through openings in reinforced sections of said plate for attaching the plate to the sole 5.

The heel cleat 7 comprises a plate of substantially isosceles trapezoid-shaped configuration in plan view and is fashioned with side, front and rear members 13, 14 and 15 respectively. The members are fashioned on the side faces of the plate and extend at right angles in relation to the horizontal plane of the plate. The plate is formed with a central aperture and is preferably constructed of aluminum to minimize weight. The ground engaging edges of the members are 15 rounded as in the instance of the members 9, 10 and 11 of the toe cleat. Likewise, the inner and outer faces of the plate are also rounded as in the instance of the toe cleat.

The toe cleat, in the preferred embodiment 20 illustrated, is particularly adaptable for use on golf shoes and the outer side member is of a greater length than the inner side member. The rear member 11 is of a greater length than the front member 10 and this construction provides 25 a tetra-point grip and effects a maximum amount of comfort to the wearer.

Figure 5 illustrates a modified form of a blank 16 formed with side members 17 of substantially the same length. This construction is particularly adaptable for use on baseball shoes wherein the wearer's foot is disposed at various angles in relation to the ground not ordinarily obtained in the playing of golf or like sports.

As clearly illustrated in Figure 3 of the drawing, each of the members are formed integral with the respective plates and the same are reinforced at the respective jointures by means of a reinforcing medium 18 which is secured thereto in any suitable manner, for instance by 40 welding.

With particular reference to Figure 4 of the drawing, the method of making the cleats, for example, the toe cleat of the preferred embodiment, consists of subjecting a one-piece metal plate 20 to a severing operation along the dotted lines 20a to form the central aperture and to a similar operation to form the laterally extending calk members 21, piercing the plate to form fastening openings thereto as indicated by the dotted lines 22, folding the calk members 21 along the dotted lines 23 to position the same at right angles to the horizontal plane of the plate, rounding the inner and outer faces of the plate as indicated 55

cated by the dotted lines 24, and rounding the ground engaging edges of the members 21.

What I claim is:

A device of the character described, comprising, a plate adapted for attachment to the sole of a shoe or the like and fashioned with front, rear and side members, said members formed on

the outer sides of said plate, and reenforcing elements secured to the inner and outer faces of said members and said plate respectively at the jointures thereof and each fashioned with an outer arcuate face extending the entire length of the 5 jointure.

RICHARD H. HAGERTY.
